[57] ABSTRACT

An internal latent image type silver halide photographic emulsion suitable for use in a light-sensitive material for the diffusion transfer process and which provides a direct positive image by surface development in the presence of a fogging agent, which emulsion is spectrally sensitized with a supersensitizing combination of at least one sensitizing dye represented by the following general formula (I)

wherein Z_1 represents a non-metallic atomic group necessary to complete a benzoxazole ring, a naphthoxazole ring, a benzothiazole ring, a naphthothiazole ring, a benzoselenazole ring or a benzimidazole ring; Z_2 represents a non-metallic atomic group necessary to complete a benzothiazole ring, a naphthothiazole ring or a benzoselenazole ring; A represents a hydrogen atom or an alkyl group; R_1 and R_2 , which may be the same or different, each represents an alkyl group or a substituted alkyl group; X represents an acid anion; and m represents 0 or 1, and at least one sensitizing dye represented by the following general formula (II), (III) or (IV):

wherein Z_3 represents a non-metallic atomic group necessary to complete a 5- or 6-membered heterocyclic ring; and R_3 and R_4 , which may be the same or different, each represents an alkyl group;

wherein Z_4 represents a non-metallic atomic group necessary to complete a 5- or 6-membered heterocyclic ring; R_5 represents an alkyl group; R_6 represents an alkyl group or a substituted alkyl group; R_7 represents a hydrogen atom or R_6 and R_7 can combine and form a ring and Y represents an oxygen atom or =N-R8, wherein R_8 represents a hydrogen atom, an alkyl group or an aryl group,

wherein V_1 , V_2 , W_1 and W_2 , which may be the same or different, each represents a hydrogen atom, a halogen atom, a trifluoromethyl group, a cyano group, a carboxy group, an alkoxy carbonyl group, an aminosulfonyl group or an alkylsulfonyl group; R_8 , R_9 , R_{10} and R_{11} , which may be the same or different, each represents an alkyl group or a substituted alkyl group; X_1 represents an acid anion; and n represents 0 or 1.
